UNITED STATES PATENT OFFICE.

WALTER M. McLEAN, OF PITTSBURGH, PENNSYLVANIA, ASSIGNOR TO W. B. McLEAN
MFG. CO., OF PITTSBURGH, PENNSYLVANIA, A CORPORATION OF PENNSYLVANIA.

DESIGN FOR A CHAIR.

12,641.

Specification for Design.

Patented June 18, 1912.

Application filed March 11, 1912. Serial No. 683,109. Term of patent 14 years.

To all whom it may concern:

Be it known that I, WALTER M. McLEAN, a citizen of the United States, residing at Pittsburgh, county of Allegheny, State of Pennsylvania, have invented a new, original, and ornamental Design for Chairs, of which the following is a specification, reference being had to the accompanying drawing, forming a part thereof.

The drawing is a perspective view of a chair showing my new design.

I claim:

The ornamental design for a chair, as shown.

WALTER M. McLEAN.

Witnesses:

ROBERT C. TOTTEN,
JOHN F. WILL.
